UNITED STATES PATENT OFFICE

2,526,411

RELIEF VALVE

Robert L. Rathmann, Tranquillity, Calif., assignor
to Rathmann Implement, Tranquillity, Calif., a
firm

Application November 25, 1947, Serial No. 788,026

3 Claims. (Cl. 137—53)

1

My invention relates to an oil filter system for hydraulic apparatus and is more specifically concerned with an attachment to be added to standard or well-known oil circulating systems for controlling heavy equipment, which makes possible the addition of a standard oil filter.

In most heavy road building equipment and farming machinery wherein equipment is controlled by hydraulic cylinders which use oil pressure, it has been found that considerable expense and time must be spent in completely overhauling and repairing the equipment because of the entry of dust and dirt into the oil supply.

The obvious solution to such a problem is by the addition of a filter for removing such dust and dirt. However, due to operating pressures involved in heavy road building and farming equipment, it has heretofore been impractical or impossible to use such oil filtering equipment.

It is an object of my invention to provide an oil filtering system whereby standard oil filters can be employed without danger of rupture because of excessive pressures.

It is a further object of my invention to provide a means for by-passing excessive pressure around a filter so that it will be impossible for excessive pressure to be built-up in the filter.

It is also among the objects of my invention to provide a simple attachment which can be applied to standard oil pressure systems for operating heavy equipment which will permit the use of a filter, thereby prolonging the effective life of the equipment and reducing the cost of expensive repairs.

Other and further objects and advantages of my invention will become apparent from the drawings and specifications relative thereto.

In the drawings:

Figure 1 shows a standard oil pressure system having my invention added thereto.

Figure 2 is a detail cross-section of the by-pass means taken on line 2—2 of Figure 1.

Figure 3 is a sectional view taken on line 3—3 of Figure 2.

Figure 4 is a schematic diagram illustrating the fluid flow in my invention.

In the drawings, Figure 1 illustrates a well-known hydraulic system which comprises a fluid reservoir tank 10, having an outlet conduit 11 communicating with a pump 12, and a pump discharge conduit 13 communicating with a directional valve 14. Conduits 15 and 16 communicate with the interior of the valve 14 and also with the hydraulic piston to be operated by the fluid pressure. Further details of the internal

2

connections will become apparent in an explanation of Figure 4.

The directional valve 14 is also formed with a mounting flange 19 adapted to mount the valve to the tank 10. The flange 19 is formed with a central bore 20 adapted to communicate with the interior of the valve 14.

The parts described up to this point constitute standard equipment and are no part of my invention. My invention resides in the addition of a by-pass valve, designated generally 30, which comprises a cylindrical housing 31 defining a chamber 32. The upper portion of the housing 31 is internally threaded, as at 33, and a plug or cap 34 is threadedly disposed therein. The plug 34 is formed with an axial bore 35 adapted to receive the valve stem 36.

Whereas, I have herein illustrated the means for closing the top of the housing 31 as a plug, such as 34, it will become apparent that the principal function of such member is to position the stem 36 and to act as a backing for a compression spring 37. Any member which will perform this function should be considered an equivalent. Other devices which could be substituted might include a plate welded to the top of the housing 31 and could be either solid or could assume the form of a spider bracket.

The lower extremity of the housing 31 is formed with a plurality of perforated sections 40, which, as will be seen, act as oil passages when the by-pass mechanism 30 functions to relieve pressure. A valve 41 is slidably disposed in the chamber 32 and is attached to the stem 36 by means of a threaded connection 42. The spring 37 is adapted to press against the top of the valve 41 urging it in a downward direction in fluid-tight engagement against a plate 43. The plate 43 is formed with a bore 44 adapted to register with the bore 20 for the passage of oil or other hydraulic fluid and is interposed between the flange 19 and the tank 10 on which the plate 43 is also formed with a bore 50 adapted to communicate with the bore 44 and having an internally threaded section 51 adapted to receive a fitting 52. A conduit 53 is secured in communication with the bore 50 by means of the fitting 52 and communicates with a filter 54. The filter 54 is of more or less standard construction and is provided with a discharge 55 which communicates with the discharge line 11 from the oil tank by means of a conduit 56.

A reference to Figure 4 will clarify the manner in which my invention operates. The valve 14 comprises a four-way valve having an inlet 14a

and discharge ports 14b, 14c and 14d. A centrally disposed core or plug 60 is formed with passageways 61 and 62. As shown in the schematic illustration, the passageway 61 communicates between the ports 14d and 14c. The passageway 62 communicates between the ports 14a and 14b so that the flow of fluid is as follows: Commencing with the pump 12, fluid is forced under pressure through the line 13, passageway 62, conduit 16 and into a hydraulic cylinder 65, thereby forcing a piston 66 and piston rod 67 to the left. Fluid which is held in the cylinder to the left of the piston 60, is forced through the line 15, passageway 61, passageway 20a, conduit 53, into the filter 54, thence out of the filter 54 through the line 56, into the conduit 11 and returned to the pump 12. However, should the pressure in the passageway 20a exceed the setting of the relief valve 30, which will be determined by the structural limits of the filter 54, such excessive pressure will be by-passed through the pressure relief mechanism 30 into the tank 10, thence out of the tank 10, through the conduit 11, and back to the pump 12.

As will be readily understood, the spring 37 (referring to Figure 2) will determine the amount of pressure against the bottom of the valve 41, which will cause the valve 41 to lift from sealing engagement with the plate 43, thereby permitting fluid to escape from the passageway 44 through the apertures 40 and into the tank 10.

Thus, it will be seen that I have provided a pressure relief system or attachment to be used in connection with standard hydraulic systems, which permits the use of filtering devices which will substantially clean the hydraulic fluid used in the system, thereby preventing excessive wear on the pump and the hydraulic control pistons.

While I have herein shown and described my invention in what I have conceived to be the most practical and preferred embodiment, it is recognized that departures may be made therefrom within the scope of my invention, which is not to be limited to the details disclosed herein, but is to be accorded the full scope of the claims so as to embrace any and all equivalent devices.

Having described my invention, what I claim as new and desire to secure by Letters Patent is:

1. A pressure responsive valve adapted to provide stepped volumetric fluid flow therethrough in response to pressures imposed thereon comprising a hollow member having a cylindrical bore therethrough, a closed end portion, and an open end portion; a base member receiving the open end portion of the hollow member and circumscribing said member for an appreciable distance from the open end portion, said base member providing an annular seat concentric to the cylindrical bore of the hollow member, normal to the axis of said bore, and defining a fluid supply bore concentrically of the annular seat; the hollow member being slotted from its open end portion to positions appreciably beyond the portion circumscribed by the base member; a valve mounted for slideable movement axially of the member between a position seated on the annular seat, a position retracted into the hollow member removed from the circumscribing portion of the base member; and a spring mounted under initial compression between the closed end of the hollow

member and the valve whereby the valve is seated when pressures less than a predetermined magnitude are impressed thereon through the supply bore, pressures slightly in excess of the predetermined magnitude displace the valve from seat engagement for fluid flow between the valve and the circumscribing base member longitudinally of the slots, and further increase of pressure further removes the valve from within the base member for direct fluid flow radially of the hollow member through the slots.

2. A by-pass valve comprising a base plate having a flat surface, a supply bore formed therethrough normal to the flat surface, and an exhaust bore formed in communication with the supply bore within the base plate, a mounting plate secured to the base plate in fluid tight engagement with the flat surface and having a counter bore formed therein concentrically of the supply bore; a hollow cylinder having spaced, annularly arranged, axially extended legs mounted in the counter bore of the mounting plate; a valve slideably mounted in the cylinder and legs for movement between a position seated on the flat surface of the base plate in covering relation to the supply bore and a position retracted in the cylinder spaced from the base plate; a stem mounted by the valve and axially extended relative to the cylinder; a closure member mounted in the cylinder opposite the valve from the base plate and slideably receiving the stem; and a spring positioned under initial compression between the valve and the closure member.

3. In a filter system for hydraulic control systems, a by-pass valve comprising a base plate having a flat upper surface, a fluid supply bore formed therethrough normal to the flat surface, and an exhaust bore formed in communication with the supply bore; a fluid reservoir having a mounting plate defining a bottom therefore secured to the base plate in fluid tight engagement with the flat surface of the base plate and having a counter bore formed therein concentrically of the supply bore; a hollow cylinder having spaced, annularly arranged, axially extended legs mounted in the counter bore of the mounting plate inwardly of the reservoir; a valve slideably mounted in the cylinder and legs for movement between a position seated on the flat surface of the base plate in covering relation to the supply bore and a position retracted in the cylinder spaced from the base plate; a stem mounted by the valve and axially extended relative to the cylinder; a closure member mounted in the cylinder opposite the valve from the base plate and slideably receiving the stem; and a spring positioned under initial compression between the valve and the closure member.
